AUTOMATIC FIRING ACTION FOR GUNS

William F. Kellotat, Portland, Oreg.

Application July 22, 1931. Serial No. 552,523

9 Claims. (Cl. 42—3)

(Granted under the Act of March 3, 1883, as
amended April 30, 1928; 370 O. G. 757)

The invention described herein may be manufactured and used by or for the Government for governmental purposes, without the payment to me of any royalty thereon.

5 This invention relates to an automatic firing action for guns.

The purpose of the invention is to provide a full automatic firing action particularly suited for light weapons, such as the .22 calibre, in which the breech block or slide is not locked in battery. The firing action, as designed, is adapted for incorporation in an existing gun by replacing and modifying only a few elements of the semi-automatic firing mechanism of the gun.

15 The invention is characterized by a sear actuator that is axially displaceable to operate the sear and that is elevated by the breech block when out of battery and depressed by a member on the block as the block arrives in battery.

20 With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

The invention is illustrated in the accompanying drawing as embodied in a pistol and in which:

25 Fig. 1 is a view in left side elevation and partly in section of a pistol equipped with the improved firing mechanism.

30 Fig. 2 is a fragmentary view similar to Fig. 1, and showing the breech block in full recoil with the trigger bar in inoperative position.

35 Fig. 3 is a view similar to Fig. 2 and showing the trigger-bar in inoperative position.

Fig. 4 is a plan view of the frame.

Fig. 5 is a bottom plan view of the breech block.

40 Fig. 6 is a detail view of the trigger bar.

Fig. 7 is a view in rear end elevation of the pistol.

The pistol represented in the drawing is generally similar to that shown in Patent No. 1,276,716 of August 27, 1918, as modified in Patent No. 45 1,277,379 of September 9, 1918. Its principle parts comprise a main frame 5, barrel 6, breech block 7 and butt piece 8. The frame carries the hammer 9, sear 10, for holding the hammer in cocked position, and a pivotally mounted trigger bar 11 reciprocal to move the sear from engagement with the hammer when actuated by a trigger 12.

The frame (Fig. 7) is provided externally with longitudinal ribs 13 and grooves 14 and the breech block has corresponding internal grooves 15 and 50 ribs 16 by which the breech block when placed on

the frame from the rear is vertically confined and horizontally guided during reciprocation. The block carries the firing pin 17 and is checked on recoil and returned to battery by a reaction spring 18 confined between it and the butt piece.

30 Of the parts hereinbefore enumerated the only replacement in the weapon of the patents is the trigger bar 11 and in this member the pivot 19 for connecting it to the trigger remains unchanged. On the rear or free end of the trigger bar there are a pair of laterally projecting lugs, (Fig. 6) the outside lug 20 whose bottom face constitutes a cam face 21 and the inside lug 22 whose bottom face constitutes a cam surface 23. The inside lug 22 is inserted through a recess 24 35 (Figs. 3 and 4) in the upper margin of the side plate of the frame so that it may be disposed within the frame and available to the sear as will be more fully described hereinafter.

The shank of the trigger bar is disposed in a 40 channel 25 formed in the left side plate of the frame below the groove 14. The channel is progressively enlarged to the rear by tapering to permit elevation and depression of the trigger bar about its pivot from the normal assembled position shown in Fig. 1.

The shank of the trigger bar is disposed in a

channel 25 formed in the left side plate of the frame below the groove 14. The channel is progressively enlarged to the rear by tapering to permit elevation and depression of the trigger bar about its pivot from the normal assembled position shown in Fig. 1.

75 Referring to Figs. 2 and 5 the rib 16 of the breech block is interrupted intermediate its length by a cut-out 26. The extremities of the forward portion of the divided rib are beveled, 80 the front bevel 27 serving to engage the outside lug 20 of the trigger bar and depress the same when assembling the breech slide on to the frame and the rear bevel 28 serving to engage the lug 20 and elevate the trigger bar during initial retraction of the breech block from the in-battery position. The front bevel 27 is on the existing gun of the patent but it is apparent that the front bevel could be reversed and made to act similar to the rear bevel in elevating the trigger 85 bar during assembly of the breech block on the frame.

90 Secured to the forward bolt portion 29 of the breech block is a rearwardly and downwardly inclined depressor finger 30 whose position laterally of the block is toward the left side so that it is capable of engaging the upper face of the inside lug 22 of the trigger bar. The frame is provided with a recess 31 and the butt piece with a recess 32 to accommodate the finger at the extremities of the stroke of the breech block. The frame in addition has a cut-out 33 to permit 95

passage of the finger when assembling the slide onto the frame. The normal position of the parts is shown in Fig. 1, the block being in battery and

the hammer cocked. The trigger bar 11 is to the rear, the inside lug 22 of the trigger bar is held in engagement with the depressor finger 30 by the trigger spring 12a and the cam face 23 on the lug 22 is just out of contact with the beveled face 10a of the sear 10. When the trigger 12 is pulled to the rear the trigger bar 11 is moved forwardly and since the lug 22 is constrained against elevation by the depressor finger 30 it will engage the beveled face 10a of the sear and rotate the sear forwardly. This movement of the sear releases the hammer in the accustomed manner to fire the gun.

As the breech block commences its recoil movement the rear bevel 28 of the rib 16 engages the outside lug 20 of the trigger bar and elevates the trigger bar as shown in Figs. 2 and 3. With the trigger released and the trigger bar in the rearward position (Fig. 2) the inside lug 22 will be depressed by the finger 30 as the breech block arrives in battery at termination of the counter-recoil stroke. The lug will thereupon assume the position relative to the sear as shown in Fig. 1.

In order to obtain full automatic action of the firing mechanism the trigger is held back and the trigger bar is maintained in the forward position shown in Fig. 3 during the recoil and counter-recoil of the breech block. The inside lug 22 is now directly over the sear so that when it is depressed by the finger it will act on the sear and force it forward by virtue of the engagement of the beveled faces 23 and 10a. The sear thus releases the hammer to strike the firing pin 12. The trigger bar is elevated by the rib 16 during the recoil stroke of the breech block so that the automatic action will be continuous as long as the trigger is held back. When the trigger is released the firing mechanism ceases to function.

Because the hammer is released and starts to rotate forwardly before the block is fully in battery a clearance is established at the rear of the bolt portion 29 of the block as indicated by the beveled surface 34 in Fig. 5.

It is to be understood that while the improved firing action has been illustrated and described as adapted to a pistol of a particular character it may be provided as a separate and complete mechanism for any type of weapon.

I claim:

1. In a gun, a frame, a breech block, a slidable connection between the block and frame, an interruption in said connection, a pivoted sear within the frame, a trigger bar reciprocally and pivotally mounted on the outside of the frame, a trigger for reciprocating the trigger bar, laterally extending lugs on the rear end of the trigger bar disposed in the interruption of the sliding connection between the block and frame, the outside lug disposed in the path of the block whereby it is elevated and held in the elevated position by the block when the block is out of battery, the inside lug normally disposed in rear of and above the sear, and a finger on the block engageable with the inside lug when the block is in battery and arriving in battery to depress the lug.

2. In a gun, a frame, a breech block reciprocally mounted on the frame, a pivoted sear within the frame, a trigger bar reciprocally and pivotally carried by the frame, means for reciprocating

the trigger bar, laterally extending lugs on the rear end of the trigger bar, one of the lugs disposed in rear of the sear, means on the block engageable with said lug to depress the trigger bar when the block is in battery and arriving in battery, and means on the block engageable with the other lug when the block is out of battery to elevate the trigger bar.

3. In a gun, a frame, a breech block reciprocally mounted on the frame, a pivoted sear carried by the frame, a trigger bar carried by the frame and having a sear-engaging portion, means for axially moving the trigger bar to release the sear, means on the block for pivotally elevating the sear-engaging portion of the trigger bar when the block is in movement, and means on the block for depressing the trigger bar into sear engaging position as the block arrives in battery.

4. In a gun, a frame, a breech block reciprocally mounted on the frame, a sear carried by the frame, a trigger bar having a lug adapted to engage the sear, means for axially displacing the trigger bar to move the sear, means on the block for elevating the trigger bar, and means on the block for depressing the trigger bar, said depression of the trigger bar providing movement of the sear when the trigger bar has been axially displaced when elevated.

5. In a gun, a frame, a breech block reciprocally mounted on the frame, a sear carried by the frame, a trigger bar for actuating the sear, means for manually moving the trigger bar, means on the block for elevating the trigger bar to inoperative position when the block is out of battery, and means on the block for depressing the trigger bar into sear engaging position as the block arrives in battery.

6. In a gun, a frame, a breech block reciprocally mounted on the frame, a sear carried by the frame, a trigger bar for actuating the sear, means for manually moving the trigger bar, means on the block for elevating the trigger bar to inoperative position when the block is out of battery, and means for depressing the trigger bar into sear engaging position as the block arrives in battery, whereby the sear is automatically released while the trigger bar is maintained in its manually moved position.

7. In a gun, a frame, a breech block reciprocally mounted on the frame, a sear carried by the frame, a trigger bar engageable with the sear, means for axially displacing the trigger bar to move the sear, means for elevating the trigger bar and means for depressing the trigger bar to move the sear.

8. In a firing mechanism for guns, a sear, a sear actuator, cooperating cam faces on the sear and sear actuator, means for axially displacing the sear actuator to actuate the sear and means for displacing the sear actuator in a plane substantially perpendicular to its axis to actuate the sear.

9. In a gun, a frame, a breech block reciprocally mounted on the frame, a sear carried by the frame, a sear actuator carried by the frame, and means on the block for operating the sear actuator to release the sear as the block arrives in battery.

WILLIAM F. KELLOTAT.
